(57) CLAIM

The ornamental design for a silicone rubber head for cosmetic purposes, as shown and described.

DESCRIPTION

FIG. 1 is a perspective view of a silicone rubber head for cosmetic purposes showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of a silicone rubber head for cosmetic purposes shown with the handle engaged.

The broken lines in the drawing are for illustrative purposes only and form no part of the claimed design.
